[57] CLAIM

The ornamental design for a tub shell for hydrotherapy spa or the like, as shown and described.

DESCRIPTION

FIG. 1 is a top, front perspective view of a tub shell for a hydrotherapy spa or the like, showing our new design; FIG. 2 is a top, rear perspective view thereof;

FIG. 3 is a top plan view thereof.

FIG. 4 is a cross-sectional view taken on line 4—4 of FIG. 3;

FIG. 5 is a cross-sectional view taken on line 5—5 of FIG. 3; and

FIG. 6 is a cross-sectional view taken on line 6—6 of FIG. 3.

The fragmentary broken line representation of a deck in FIGS. 1 and 2 is for the purpose of illustration only.

FIG. 1
